GARMENT HANGER

Henry Spitz, Great Neck, N. Y.

Application June 14, 1954, Serial No. 30,965

Term of patent 14 years

(Cl. D80—8)

FIG. 2

To all whom it may concern:

Be it known that I, Henry Spitz, a citizen of the United States of America and a resident of the town of Great Neck, county of Nassau and State of New York, have invented a new, original, and ornamental Design for a Garment Hanger, of which the following is a specification, reference being had to the accompanying drawing, forming a part hereof, wherein,

Fig. 1 is an elevational view of a garment hanger showing my new design; and

Fig. 2 is a section taken along line 2—2 of Fig. 1.

The dominant features of my design reside in the portion shown in full lines.

I claim:

The ornamental design for a garment hanger, substantially as shown and described.
